CLAIM

The ornamental design for a micro-exfoliation roller, as shown and described.

DESCRIPTION

FIG. 1 is a top plan view of a micro-exfoliation roller showing our new design;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a perspective view of a micro-exfoliation roller showing our new design.
The broken lines in the drawings are for the purposes of illustrating portions of the article that form no part of the claimed design.

1 Claim, 7 Drawing Sheets
